UNITED STATES PATENT OFFICE

165,740

PLAYING UNIT FOR GAME TABLES OR SIMILAR ARTICLES

Sidney T. Cooper, Plainview, Tex.

Application August 16, 1949, Serial No. 4,523

Term of patent 3½ years

(Cl. D34—5)

To all whom it may concern:

Be it known that I, Sidney T. Cooper, a citizen of the United States, residing in Plainview, in the county of Hale, in the State of Texas, have invented a new, original, and ornamental Design for a Playing Unit for Game Tables or Similar Articles, of which the following is a specification, reference being had to the accompanying drawing, forming part thereof.

Fig. 1 is a top plan view of a playing unit for game tables or similar articles, showing my new design.

Fig. 2 is a perspective view thereof; and

Fig. 3 is a side elevational view thereof, a portion being broken away.

I claim:

The ornamental design for a playing unit for game tables or similar articles, as shown.

SIDNEY T. COOPER.
